UNITED STATES PATENT OFFICE.

JOHN E. BUORK, OF CHARLOTTESVILLE, VIRGINIA.

SNOW-SKATE.

1,213,739.

Specification of Letters Patent.

Patented Jan. 23, 1917.

Application filed August 29, 1916. Serial No. 117,475.

To all whom it may concern:

Be it known that I, JOHN E. BUORK, a citizen of the United States, residing at Charlottesville, in the county of Albemarle and State of Virginia, have invented certain useful Improvements in Snow-Skates, of which the following is a specification, reference being had therein to the accompanying drawing.

10 The object of my invention is to provide a skate comprising a runner of peculiar construction, and having attached thereto the front end of a foot plate, adapted to oscillate vertically, to adapt itself to the various 15 positions of the skater's foot.

Further objects of the invention will appear in connection with the description of the construction hereinafter described and claimed.

20 Reference is to be had to the accompanying drawings in which like reference characters denote like parts throughout the several views.

Figure 1 is a side elevation of a skate constructed in accordance with my invention. Fig. 2 is a bottom plan view of the same. Fig. 3 is an enlarged vertical section on the line 3—3 of Fig. 1. Fig. 4 is a similar view on the line 4—4 of Fig. 1.

30 In the drawings, the skate runner is shown formed of a single piece of metal comprising a flat relatively narrow longitudinally extending ground engaging portion 1, upwardly curved at its front end, and upwardly bent sides 2 joined together at their upper edges to form the runner.

Between the ends of the runner, but nearer the front end thereof, the sides 2 are extended upwardly adjacent each other to 40 form a support 3, and are then curved outwardly to either side as shown at 4, to form supporting plates. A foot plate 5 of suitable shape and formed of spring material is riveted at its front end to the plates 4, 45 its rear end being free, and adapted to oscillate in a vertical plane. The sides 2 of the runner are also extended upwardly for a short distance to form a support 6 beneath the rear end of the foot plate.

50 The shoes of the skates having been secured to the foot plates in any approved

manner, it will be seen that when the weight of the skater is placed upon the skate, the rear end of the foot plate will be bent downwardly and rest upon the support 6, but as 55 the skater's weight is thrown forward in making a stroke, the foot plate, being made of resilient material, will have a tendency to spring upward as shown in Fig. 1, thereby adapting the foot plate to the bend of 60 the skater's ankles.

I claim:

1. The combination in a skate of a runner comprising a ground engaging surface and upwardly bent sides joined together at their 65 upper edges, the said sides being upwardly extended intermediate of the ends of the runner to form a support, the upper ends of the said extensions being outwardly turned to form supporting plates, a foot plate 70 formed of resilient material secured to the said supporting plates at its front end, the sides of the said runner being upwardly extended to form a support beneath the rear end of the said foot plate. 75

2. A skate runner comprising a ground engaging surface and upwardly bent sides joined together at their upper edges.

3. In a skate the combination with a runner having upwardly extending sides 80 intermediate of its ends forming a support, the upper ends of the said extensions being outwardly turned to form supporting plates, of a foot plate secured to the said supporting plates and adapted to oscillate in a vertical plane. 85

4. In a skate the combination with a runner, of a support, a foot plate secured at its front end to the said support, and adapted to oscillate in a vertical plane, the sides of 90 the said runner being upwardly extended to form a support beneath the rear end of the said foot plate.

5. The combination in a skate of a runner, a support, a foot plate formed of resilient material secured at its front end to the said support, and a second support upon the said runner beneath the rear end of the said foot plate. 95

In testimony whereof I affix my signature. 100

JOHN E. BUORK.
